UNITED STATES PATENT OFFICE

2,436,478

DEVICE FOR PRODUCING AEROSOLS

Arthur W. Lindquist, Chester N. Husman, and Herman O. Schroeder, Orlando, Fla., assignors to United States of America, as represented by the Secretary of Agriculture

Application September 6, 1944, Serial No. 552,860

1 Claim. (CL 299—88)

(Granted under the act of March 3, 1883, as amended April 30, 1928; 370 O. G. 757)

1

This application is made under the act of March 3, 1883, as amended by the act of April 30, 1928, and the invention herein described and claimed, if patented, may be manufactured and used by or for the Government of the United States of America for governmental purposes without the payment to us of any royalty thereon.

This invention relates to a device for the production of finely atomized sprays of the type known as aerosols for the control of mosquitoes, flies, gnats, and other insects.

An object of this invention is the combining of an air pump and liquid tank in a compact, convenient unit which can be carried on the person, stored easily, and packed and shipped with a minimum of weight and space.

Another object is to avoid leakage of liquid when the device is not in use irrespective of the position in which it might be placed.

Further objects are the provision of means to increase the discharge rate of the spray and to produce finely atomized droplets or aerosols that remain suspended in the air for considerable periods of time.

Other objects and advantages of the invention will be apparent from the following description, considered together with the accompanying drawing.

In the drawing:

Fig. 1 is a top plan view of a pocket-size embodiment of the device showing it ready for use.

Figure 2 is a vertical section of the device showing parts in position when it is not in use; and

Figure 3 is a section along the line 3—3 of Fig. 1.

Referring with more particularity to the drawing in which like numerals designate like parts, a container 11, preferably fabricated of a suitable metal with crimped edges, is divided into two compartments, one of which is of cylindrical shape and comprises the barrel of an air pump and the other comprises a tank 12 for holding the liquid to be dispersed. A leather piston 13 and supports 14 are mounted on a plunger rod 15, which is supported by a cap 16, all enclosed in the cylinder 17, forming an air pump. By actuating the plunger rod 15 by means of the handle 18, ejection of air through a plurality of orifices 19 at the end of air pump cylinder 17 is accomplished. For larger sizes in commercial applications, air or other gases may be supplied by machine-powered equipment (not shown) instead of the hand pump.

A feed or dip tube 20 terminating at a point

5 near the rear of the tank 12 is slightly elevated from the bottom of the tank 12 and extends to a valve 21. The body of the valve is disposed inside the container and the needle valve 22, needle control 23, and packing nut 24 are disposed outside the front end of the container. Feed tubes 25 extend from the valve 21 inside the container through the wall 26 and on the outside of the container, they are connected to capillary tubes 27. Each capillary tube extends to a point opposite one of the orifices 19. These capillary tubes should, preferably, have an orifice diameter of about 0.017 inch (inside diameter) and a wall thickness of about 0.001 at the outlet.

10 Struts 28 are secured inside the container 11 to strengthen it and thereby prevent undue expansion and retraction of the walls. Such expansion and retraction would cause ejection of liquid through the capillary tubes in a coarse stream which is not desirable.

15 A screw cap 29 covers the filling aperture 30 of the tank. A hood 31, above the nozzles, is attached to the container and a slide 32 covers the ends of the capillary tubes 27 when moved 20 in one direction and uncovers them when moved in the opposite direction. The slide is carried on the tubes 25 which serve as guide tracks. A plate 33, which is rigidly secured to the outside of wall 26 in a substantially superimposed position over cylinder 17, and which contains a plurality of orifices in direct alignment with orifices 19, is also provided. This plate 33 serves as a means for carrying hood 31.

25 In operation, this device will discharge concentrated insecticides in an exceedingly fine mist which remains suspended, and consequently effective, in the air for prolonged periods of time.

30 To put the device into operation, the ends of the capillary tubes 27 are exposed by moving the slide 32 toward the valve 21. The valve is then opened and the pump actuated with the handle 18. This delivers air over the ends of the capillary tubes, thereby pulling liquid from the tank and atomizing it into a spray or mist of 35 very fine particles. When a sufficient amount of the mist has been dispensed, the plunger is pushed in and the handle locked in position. Also, the valve is closed and the slide moved in position to cover the ends of the capillary tubes 40 45 50 55 27. In this condition, the container may be placed in a pocket on the person or stored in any position without danger of leakage.

This device, although generally useful for the dispensing of insecticides, may be used to dispense any other liquids desired. We have found

that 0.5 cc. of a liquid containing about 20 to 25% active insecticidal ingredients is effective for a space of about 1,000 cubic feet when dispensed by a device of this kind.

Biological tests with flies show the great superiority of our device over other types of sprayers. For example, the 24-hour mortality of houseflies exposed to the atomized spray produced by our device at intervals of 15, 30, and 60 minutes was 62, 37, and 15 percent, respectively. Other types of sprayers gave mortalities of only 30, 20 and 4 percent when exposed in the same manner.

Similar biological tests on mosquitoes with our device gave mortalities of 70, 30, and 7 percent as compared to other sprayers giving mortalities of 26, 10, and 4 percent.

Having thus described our invention, we claim:

A device for producing aerosols comprising a container for holding a liquid, an air pump in said container, said container having a plurality of apertures for the discharge of air from said pump, capillary tubes on the outside of the container, each terminating at a point in the path of air discharged from one of said apertures, a valve, said capillary tubes being connected to the outlet of said valve, a shield slidably mounted on said container for covering the ends of said tubes when the device is not in use and for uncovering said ends when the device is to be used, a hood secured to said container in the line of movement of said slide for engaging the end of said slide when

the slide is in a position covering said ends, a dip tube within the container having one end connected to the inlet of said valve and the other end disposed near the bottom of said container, said pump having a reciprocable plunger rod extending from the bottom of the container, the outer end thereof being provided with a handle to fit against the bottom of the container when the plunger is in a retracted position.
